Patented May 2, 1916.

FIG. 3.

Inventor
Garth Griffith Gilpin
By *George S. Jackson*
His Attorney

UNITED STATES PATENT OFFICE.

GARTH GRIFFITH GILPIN, OF RIVERSIDE, ILLINOIS, ASSIGNOR TO WALTER P. MURPHY, OF CHICAGO, ILLINOIS.

UNCOUPLING-LEVER.

1,181,952.

Specification of Letters Patent. Patented May 2, 1916.

Original application filed April 24, 1912, Serial No. 692,837. Renewed November 8, 1915, Serial No. 60,419. Divided and this application filed January 26, 1915. Serial No. 4,431.

To all whom it may concern:

Be it known that I, GARTH GRIFFITH GILPIN, a citizen of the United States, residing at Riverside, in the county of Cook and 5 State of Illinois, have invented certain new and useful Improvements in Uncoupling-Levers, of which the following is a specification.

One of the principal objects of the invention is to provide a device of novel construction in which a rigid link is utilized 10 for lifting the locking pin of the coupler, this link being directly connected with the locking pin and with the operating member 15 of the uncoupling device by connections which allow the coupler perfect freedom in its normal intended movements, both lateral and longitudinal, and which furthermore permit an easy, free and unimpeded manipulation of the device during the operation 20 of raising the locking pin.

A further object is to do away with clevises, bolts, pins and other parts of like character which are apt to be injured or 25 which may be lost when an uncoupling device comprising such parts is detached from the coupling for the purpose, for example, of repairing the latter and at the same time to provide an arrangement 30 whereby the operative connection between the uncoupling mechanism and the lock pin of the coupler is maintained under service conditions and also as against accident to and tampering with the device.

35 A further object is to provide a device of the general character herein shown which will operate to automatically raise the locking pin upon an abnormal forward movement of the coupler due to the failure of 40 the coupler or some of its connections.

A further object of the invention is to provide an uncoupling device which will be very simple in its construction, economical to manufacture, strong, durable and reliable and effective in its operation.

In the drawings: Figure 1 is a fragmentary view in elevation of the end of a car with my improved uncoupling lever applied. Fig. 2 is a side elevation of Fig. 1. 50 Fig. 3 is an enlarged detail front elevation showing, in dotted lines, the coupler pin link in different positions to accommodate the lateral movement of the coupler. Fig. 4 is an enlarged detail side elevation, also

showing, in dotted lines, the coupling pin 55 link in different positions to accommodate the forward and rearward movement of the drawbar in draft and buff. Figs. 5 and 6, 60 are, views, at right angles to each other, of one form of pin links.

Reference numeral 9 designates the end 65 of a car (broken away), 10 the dead wood, and 11 the coupler resiliently mounted on the car, all of which may be of any approved construction.

The hand operated lever 12 is provided 70 with a crank at each end at right angles to each other, the crank 13, depending below the underface of the car, when the lever is attached to the car and serving as a handle with which to operate the lever 12, while the crank 14, at the inner end of the lever, projects forwardly from the car to a point in a plane perpendicular to the lock pin 15 of the coupler, an eye being formed 75 on the end of the crank 14 in a horizontal plane. The lever 12 is secured to the car by means of the brackets 17 and 18 each provided with an opening through which the lever passes, said openings being of 80 slightly greater diameter than the lever in order that the lever may have a slight play therein. The bracket 17 is provided with a stop 19 to limit the inward movement of 85 the lever.

The connection between the lever 12 and the lock pin 15 of the coupler consists of a single rigid bar link 20 terminating in hooks 21 and 22 at each end disposed at right angles to each other, the end of the hook 21 90 being deflected to one side as clearly shown in Figs. 2, 3, and 6. It will be observed that the end of hook 22 normally stands close to the crank 14 so that the link can be turned or rotated with respect to its longitudinal 95 axis to an appreciable extent only in one direction. This permits the lower or deflected hook to be engaged with the lock pin when the apparatus is installed on the car, that is before the brackets are attached, and 100 similarly the disengagement of the deflected hook from the lock pin provided the operating rod be dismounted from the car. On the other hand with the rod in place on the car there can be no other accidental disengagement of the hook 21 from the lock pin 105 because rotation in the opposite direction is necessary before such disengagement can

be effected and this is prevented by the end of the hook 22 striking against the crank 14. The open hook 22 engages the eye 16 of the lever 12 and forms therewith a flexible joint between the lever and link, while the hook 21 engages the eye 15 of the lock pin and forms therewith a flexible joint. The upper end of the link 20 extends loosely through and projects beyond the eye 16 on the crank; the hook 22 providing means for retaining the link in the eye. The under surface of said eye provides a rounded bearing for engagement with said eye 16 on the crank.

15 The positioning of the flexible joint between the lever and the link in a plane perpendicular to the lock pin enables the link to travel with the coupler forward, under draft strains, and rearward under buff, 20 without any binding or interlocking action between the link and lever, and also permits the link to move sidewise with the lateral movements of the coupler without binding or interlocking action between the lever and link; the joint between the lever and link being, in effect, a universal joint.

In case of extreme forward travel of the draw bar in the event of its breaking or becoming loosened from its ³⁰ orings, or in the event of the failure of the draft gear yoke or other parts of the draft gear, the link upon reaching the limit of its swinging movement withdraws the lock pin and permits the knuckle of the coupler to open thus uncoupling the two couplers and relieving the damaged draw bar from further pull and permitting it to remain in some of its bearings suspended from the car, thus 35 eliminating the danger incident to its dropping on the road bed.

This is a divisional application of my application filed April 24, 1912, Serial No. 692,837, renewed as Serial No. 60,419, Nov. 8, 1915. I do not claim in this application 40 the invention common to this application and my co-pending application, Serial No. 68,211, filed Dec. 22, 1915 as such generic invention is claimed in said application, Series No. 68,211, which is a division of 45 692,837.

I claim:

1. In combination, a car, a coupler resiliently mounted on the car and having a lock pin which is raised to unlock the same, and a release rigging comprising a revoluble rod formed with a crank having an eye, a rigid link provided at its lower end with an open hook the end portion of which is deflected from the plane of the link and the rest of the hook, the upper portion of the link extending and vertically slidably in the eye of the crank and provided with means forming a stop adapted to bear against the crank so as to limit the axial rotation of the link in

the direction which would allow disengagement of the link, to prevent such disengagement.

2. In combination, a car, a coupler resiliently mounted on the car, a lock pin which is raised to unlock the same, and a release rigging comprising a revoluble rod formed with a crank having an eye, a rigid link capable of vertical movement with respect to the lock pin provided at its lower end with an open hook the end portion of which is deflected from the plane of the link and the rest of the hook, and with a return bend at its upper end extending through said eye and forming a stop adapted to engage the crank to prevent revolution on a substantially vertical axis of the link in the direction which would allow the disengagement of the hook from the lock pin.

3. In a release rigging for resiliently mounted car couplers having a lock pin which is raised to unlock the same, an operating rod, a crank on said rod, a rigid link flexibly connected with the crank and rotatable about its longitudinal axis to be connected to and from the lock pin, and means to prevent axial rotation of the link in the direction which would allow disengagement of the link from the lock pin when mounted on a car.

4. In a release rigging for a resiliently mounted car coupler having a lock pin which is raised to unlock the same, an operating rod provided with a crank having an eye, a rigid link rotatably mounted and vertically slidably in said eye, an open hook at the lower end of said link the end portion of which is deflected from the plane of the link whereby the link must be given an approximately spiral movement to connect and disconnect said open hook to and from the lock pin, and means constituting a stop between the link and said crank so as to prevent the rotation on a substantially vertical axis of the link in the direction which would allow its disengagement from the lock pin when mounted on a car.

5. In combination with a car, and a coupler resiliently mounted on the car having a lock pin provided with an eye, of a release rigging comprising a rod revolvably mounted on the car and having a crank, a single link having an open hook at its lower end to extend through said eye, and a connection between the link and crank permitting the link to swing angularly in all directions and to move in the direction of its length with respect to the crank but preventing rotation of the link with respect to the crank a distance sufficient to cause a disengagement between said hook and lock pin.

6. In a car coupler uncoupling device, the combination with the lock pin of the coupler having an eye, of an operating rod rotatably mounted on a car, a lever on said

rod projecting forwardly from the end of the car and extending over the coupler and terminating in an eye disposed vertically over said pin; a single rigid link connecting the eye of the crank with the eye of the locking pin; said link terminating at its upper end in a return bend portion for engagement with the eye of the lever, and terminating at its lower end in a hook extending transversely of the coupler and engaging the lock pin eye, the joints between the said eyes and the said link constituting flexible joints which permit of the normal longitudinal and transverse movements of the coupler without imposing strain on said lever.

7. In a release rigging for an automatic car coupler, the combination with an uncoupling rod revolvably mounted on the end of

the car and having a depending crank at its outer end and a crank arm at its inner end extending forwardly from the car to a point over the coupler head, and at right angles to the depending crank and terminating in an eye, of a bar link terminating in a hook at each end, the hook at one end loosely engaging the eye of the uncoupling rod crank to permit of a vertical movement of the link relative to said eye while the hook at the other end of said link engages the eye of the locking pin.

In testimony whereof I affix my signature in presence of two witnesses.

GARTH GRIFFITH GILPIN.
